UNITED STATES PATENT OFFICE.

SAMUEL HAYWARD, OF BOSTON, MASSACHUSETTS, ASSIGNOR TO J. ESTEY & CO., OF BRATTLEBOROUGH, VERMONT.

DESIGN FOR ENDS OF AN ORGAN-CASE.

Specification forming part of Design No. **6,680**, dated May 27, 1873; application filed April 25, 1873.

To all whom it may concern:

Be it known that I, SAMUEL HAYWARD, of Boston, in the State of Massachusetts, have invented a Design for an Organ-Case, of which the following is a specification:

The nature of my design is fully represented in the accompanying photographic illustration, to which reference is made; and it consists in the shape of the projecting portion at the rear, extending vertically from the base to the top.

In the photographic illustration, B represents the end of the case, from the rear portion of which projects the column A, extending from the base to the top, its surface being parallel with the plane of the end, and the

projection producing an appearance of effective relief. These columns relieve the ordinary plain and flat appearance of the ends of the case, imparting a bold appearance combined with simplicity of design.

I claim as my invention—

The design for the ends of an organ-case, formed by the columnar projections A at such ends, substantially as shown and described.

In witness whereof I have hereunto signed my name in the presence of two subscribing witnesses.

SAMUEL HAYWARD.
